UNITED STATES PATENT OFFICE.

HENRY C. BREIDENBACH, OF DAYTON, OHIO.

VENEER-LOG-SCORING MECHANISM.

Application filed November 17, 1926. Serial No. 148,881.

My invention relates to veneer log scoring mechanisms, and more particularly to mechanisms for dividing the cylindrical or conical surface of wood stock, which is to be planed off into veneer sheets by rotating same in lathe manner, against a shearing blade, and consists substantially in the construction, combination and arrangement of parts hereinafter set forth and pointed out more particularly in the claims.

It is an object of my invention to provide a travelling saw, which may be manually or otherwise fed into the revolvably supported veneer stock, and guided longitudinally thru the adjacent side thereof, whereby veneer planed from same in lathe manner, will fall in economically trimmed sheets, without rough or torn edges.

It is a primary object of my invention to suspend a mechanism of this class, from an overhead horizontal guide means, by which arrangement the carriage parts of the mechanism are disposed out of the operator's way, to give ordinary free access to the veneer machine proper.

It is also an object to support the cut-off saw means by a collapsible suspension, by which arrangement same may be moved upwardly out of the way, when not in use, and fed downwardly again into working position, as desired.

It is also an object to embody with a mechanism of this class, a balancing means, to balance the weight of the saw means and parts sundry thereto, to prevent same from moving downwardly by force of gravity; and to assist in raising same.

It is an important object of the invention to provide a cut-off saw for this purpose, mounted and driven by a motor, preferably an electric motor, and to feed same thru flexible conductors, preferably carried from said motor thru said extension, and thence to a fixed source of supply, by which arrangement said saw may be readily brought to a variety of working positions, without interruption of the propelling medium.

The above and other objects are attained by the structure illustrated in the accompanying drawings, in which Figure 1 is a front fragmentary view of my invention, and associated mechanisms; Fig. 2 is a part sectional end view of Fig. 1; Fig. 3 is an enlarged sectional view illustrating the preferred means for constructing the saw carriage and horizontal guide means, and Fig. 4 is an enlarged detail

elevation, partly in section, of the meeting ends of the collapsible suspension means.

Similar characters of reference designate similar parts thruout the different views. 60

Referring to Figure 1, the numeral 1 designates the base of a lathe type veneer producing machine, in which the wood stock 2 is revolvably supported between the two center engaging means 3 and 4, which in turn are pivotally supported on said base thru the pedestal journal means 5, 6 and 7. The gear wheel 8 is co-axially connected with the center means 3, between the journals 5 and 6 by a common shaft 9; the stock 2 being thus rotated by said gear, which in turn is rotated by other gearing (not shown) in conventional manner. 70

Referring to Fig. 2, the log stock 2 is shown across sectionally, as well as is the veneer shearing knife 10, which engages the outer surface 11 of said stock in a somewhat tangent manner. Said knife has a corresponding holder 12, which by means of its gauging face, which frictionally embraces said surface, 80 keeps said knife a certain working distance within said stock in wood plane manner, by which arrangement it will be understood that revolving the stock in the direction indicated by the arrow 13 will cause veneer sheets 14 to 85 be sheared therefrom.

The circular saw 15 is disposed in coincidence with the vertical plane, which passes thru the axial center of the stock 2, as will be understood. Said saw is concentrically 90 mounted on a motor 16, preferably of the electric type, which is adapted to drive same. Said motor is therefore conveniently suspended with said saw by means of the upwardly extending hollow motor support rod 17 to 95 which said motor is integrally fixed.

At good clearing distance above the operator, the flat shaped saw carriage 18 is conveniently supported at its four corners by the roller means 19, which travel in the tracks 20. Said tracks may be similar to tracks such as are ordinarily used in supporting garage or other doors. They are secured to the ceiling joists 21, and being arranged parallel to a medial line of the stock 2 are together symmetrically arranged over same. 105

From a medial point of said carriage, a sleeve 22 extends downwardly and receives, in telescoping manner, the motor supporting rod 17. It will be obvious that vertical adjustment of the motor 16 may be attained by corresponding movement of said rod in said 110

sleeve, by which arrangement the saw 15 is lowered when cutting into the stock 2, and likewise withdrawn from cutting positions. It will be also understood that said saw is fed lengthwise with the stock 2 by shifting the carriage 18 along on the tracks 20, for the purpose of cutting a longitudinal bisecting slit, the depth of which is controlled as desired by sliding said rod downwardly in 10 said sleeve a suitable distance, for thus scoring said stock, as understood by those familiar with veneer producing machines of this class.

The cable guide wheels 22' and 23 are pivoted on said carriage by the horizontal pins 24 and the mountings 25, as will be later referred to.

The sheave wheel 26 is interposingly journaled thru the clearance slot 27 in the lower region of the rod 17, by the horizontal pivot pin 28, and is adapted to support said rod by means of the cable strands 29 and 30, which unite about the lower periphery of said pulley and extend upwardly, one from each side of same. The strand 29 runs thru a clearance hole 31 in the carriage 18, tangent to the inward groove portion of the guide wheel 22', reaching approximately 90° about same, and thence approximately horizontal to the stationary attachment 32, which is conveniently secured to an overhanging part of the building structure. The strand 30, in like manner extends upwardly thru another clearance hole (not shown) in said carriage, into tangency with the inward groove points of the guide wheel 23, and being threaded approximately 90° about same, extends outwardly therefrom in an approximately horizontal direction, to tangency with the upper points of 40 the grooved wheel 34, thence outwardly around same about 90°, and thence downwardly to the counterbalancing weight 35, which it supports. Said weight keeps the cable strands 29 and 30 taut about the sheave wheel 26, the guide wheels 22', 23, etc., and is just heavy enough to thus counterbalance the weight of the saw 15, the motor 16, the rod 17, etc., permitting said saw to be readily raised and lowered, but retaining the imposed positions of same, as will be understood by those familiar with such art.

By this arrangement the carriage 18 may be both shifted back and forth on the tracks 20, as required for the travel of the saw 15, 55 without disturbing the effectiveness of the weight 35, it being understood that the cable strands 29 and 30 run freely under the sheave wheel 26 and over the guide wheels 22' and 23, although the ends of said cable are held stationary by the attachment 32 and said weight.

The carriage 18 is actuated back and forth on the tracks 20 as desired by means of the cables 36 and 37, which extend therefrom on lines approximately parallel to the axial line 65 of the stock 2, to tangency with the upper

portions of the relatively stationary pulley means 38, and thence outwardly around same about 90°, and downwardly again to the windlasses 39 and 40, which are pivotally supported to the upright timbers 41, and 70 adapted to be manually operated by the cranks 42 and 43, respectively. By this arrangement the carriage 18 may be drawn along on the tracks 18 by the windlass 39 in the direction of same, and likewise by the 75 windlass 40 in the direction of same. The operator, therefore, is able to feed the saw 15 back and forth thru the work, by operating said windlasses cooperatively. Said hand cranks are typically mounted to said windlasses within convenient reach of the operator.

The rod 17 is keyed to the sleeve 22 by means of a pin key 44, which is preferably fixed to said sleeve, and is slidably disposed in the corresponding keyway 45 of said rod 17. This provision prevents said rod from rotating in said sleeve and hence prevents the saw 15 from being inadvertently turned to an improper cutting angle, and restricts the 90 vertical movements of same.

The motor 16 is fed by the electrical conductors 46 which run from said motor upwardly thru the rod 17 and the sleeve 22, and thence to the stationary conductor means 47 which are in turn fed from a source of electrical current supply (not shown). This permits free operation of the invention without regard to the conductors 46 and without interruption of the current supply.

The conductors 46 are of such length that the saw 15 may be successively lowered as the diameter of the stock 2 is reduced, and as best shown in Fig. 4 of the drawings, the conductors collapse within the members 17 and 22 when the saw is moved upwardly in a vertical direction so that they may readily pay out as the saw is lowered.

The blade holder 12 is mounted at its ends by the oscillatable supports 48 which are suitably pivoted to the upwardly disposed eyelets 49 of the base 1. The blade 10 is thus swung into the stock 2 to suitably shear off veneer strips of uniform thickness, as will be understood by those familiar with the art, and as said stock is thereby reduced in diameter, the saw 15 is operated from time to time as before mentioned, to precede the veneer cuts, in depth. It is understood that when the diameter of said stock is thus reduced, rotation of same is stopped, and a new cut taken with said saw, longitudinally of said stock by sliding the saw downwardly to suitable cutting height and shifting same along in said stock, by the windlasses 39 and 40, which splines said stock its full length. Rotation of said stock against the blade 10 is then continued, the veneer strips being limited to suitable size by the scores thus cut by said saw, and any number of scores may be made 125 130

longitudinally of the stock 2 and the scores spaced varying distances apart. It will likewise be understood that the strips of veneer may be made substantially uniform in width 5 by reducing the number of scores as the diameter of the stock decreases.

After the saw 15 has been adjusted to suitable position for scoring purposes or raised to inoperative position, it may be held in 10 fixed position in any suitable manner, as by means of a binding element 50.

While I have illustrated in a general way, certain instrumentalities which may be employed in carrying my invention into effect, 15 it is evident that many modifications may be made in the various details, without departing from the scope of the appended claims, it being understood that my invention is not restricted to particular forms herein 20 described.

I claim as my invention:

In a scoring device for veneer forming material, a circular saw, a motor for support-

ing and driving said saw, a hollow rod supporting said motor, said rod having a transverse slot through its walls adjacent its junction with the motor, a hollow sleeve telescopically receiving said rod, a movable carriage to which said sleeve is attached, a sheave pivotally mounted in said transverse slot the diameter of which is greater than the diameter of said rod, whereby the sheave will project a distance beyond the walls of the rod, a cable passing beneath said sheave and upwardly to said carriage, one end of said cable being anchored, a counter balance weight attached to the opposite end of said cable, guide wheels on the carriage for said cable, and feed wires passing through said hollow sleeve and rod and being collapsible 40 in said sleeve.

In testimony whereof, I have hereunto set my hand on this the 30th day of October, 1926, A. D.

HENRY C. BREIDENBACH.
